UNITED STATES PATENT OFFICE.

MEREDITH G. STANLEY, OF CINCINNATI, OHIO.

REGISTERING-STAMP.

1,067,448.

Specification of Letters Patent. Patented July 15, 1913.

Application filed May 3, 1912. Serial No. 694,887.

To all whom it may concern:

Be it known that I, MEREDITH G. STANLEY, a citizen of the United States, residing at Cincinnati, in the county of Hamilton and State of Ohio, have invented certain new and useful Improvements in Registering-Stamp, of which the following is a specification, reference being had therein to the accompanying drawing.

10 This invention relates to hand stamps and has special reference to a hand stamp adapted to give a duplicate impression, one impression being on an article exterior of the same, as for instance a bill or receipt, and 15 the other impression being on material held within the same to constitute a register of the impressions made upon the exterior.

The principal object of the invention is to 20 improve the general construction of a stamp of this character.

A second object of the invention is to provide a stamp of this character wherein the inking will be accomplished by means of inking pads of the type such as are commonly used with the ordinary hand stamp and wherein a pad of felt covered with cloth is impregnated with a suitable ink of a character that will readily lend itself to deposition on a surface pressed against the 30 same.

With the above and other objects in view this invention consists in general of certain novel constructions, combinations and arrangements of parts as will be hereinafter 35 fully described, illustrated in the accompanying drawings, and specifically claimed.

In the accompanying drawings, like characters of reference indicate like parts in the several views, and Figure 1 is a transverse 40 section through a stamp constructed in accordance with this invention. Fig. 2 is a section at right angles to Fig. 1. Fig. 3 is a detail perspective of a certain ink pad and a controlling arrangement therefor as used 45 in connection with this stamp. Fig. 4 is a detail view of a certain slide used in connection with the device. Fig. 5 is a detail view of a certain pad used for pressing a paper strip against certain characters.

50 The stamp as constructed in accordance with this invention consists in a casing 10 which is mounted upon a base casing 11 and is slidable therein, being prevented from excessive movement by inturned flanges 12

formed on the engaging portions of the two 55 casings. Within the casing 10 there is secured a frame 13 which carries a shaft 14, the latter being supported on the upper ends of springs 15 held in spring cases 16 supported on plates 17, the lower ends whereof pass through suitable slots in the casing 10 and are secured to the lower ends 11 so that the lower ends of the springs are stationary with reference to the lower casing.

It will be seen that by this construction 65 whenever the casing 10 is forced downward into the casing 11 the springs 15 will be compressed so that when the pressure is removed the casing 10 will again move upward. On the lower end of the casing 10 70 is supported a stamp 18 having suitable characters such as the name of the firm using the stamp, the word "Paid" or any other suitable inscription formed on the underside thereof. This stamp furthermore 75 has a transverse slot 19 extending thereacross and connecting the two sides of the frame 13 and lying in this slot is a bearing 20.

Carried on the shaft 14 is a series of drums 21 each of which is provided with peripheral teeth 22. Each of the drums 21 is furthermore provided with a flange 23 provided with teeth 24 between which are suitable characters 25 as will be hereinafter described. In order to rotate these drums 21 a 85 recess 26 is formed in the side of the casing 10 and in this recess is a window 27 through which the teeth 24 project. Adjacent the upper part of the frame 13 is a second cross bar 28 and around the two cross bars 20 and 90 28 lying on each side of the drums 21 is a series of endless bands 29 having printing characters 30 formed thereon. These endless bands furthermore are provided with notches 31 which engage the teeth 22 on the 95 drums 21. Each of these endless bands has a double series of characters thereon as for instance two sets of characters representing the months of the year arranged consecutively or two sets of digits similarly arranged, and these characters are so spaced that when one such character as "Jan." in one set lies beneath the plate 20 the character "Jan." of the second set will lie above the plate 28. Hinged to each side of the 105 lower casing 11 is an ink pad 31 which is normally held pressed upwardly in a horizontal position by a similar spring 32. In

this manner the ink pads bear against the stamp 18 and the character beneath the plate 20.

When it is desired to impress the characters on the stamp and beneath the bar 20 upon a surface it is simply necessary to press down upon the handle 33 fixed to the upper part of the casing and the two pads 31 will swing on their hinges and permit contact of the stamp 18 and the character beneath the plate 20 with the desired surface.

Detachably supported in the frame 13 is a shaft 34 consisting of a drum which carries a roll of paper 35. A shaft 36 is likewise detachably supported in the frame 13 and on this shaft is wound the paper rolled off from the drum 34, the shaft 36 thus constituting a paper-receiving drum. The shaft 36 is furthermore provided with a ratchet 37 which is adapted for engagement with a toothed bar 38 which extends downward within the casing 10 and passes through a slot 39 to the outside of the casing, the lower end of the bar being secured to the casing 11 at 40. The upper end of this bar is reduced so as to form a spring so that the teeth thereon may yieldably engage with the teeth of the ratchet 37. At each side of the frame 13 there is carried a pair of spaced ribs 41 arranged to form a guide wherein slides a plate 42 provided with an opening 43 adjacent each of its sides. Secured to the casing 11 and extending inward through slots 44 are bars 45 each of which supports a cam 35 consisting of two triangular plates connected at their apices as indicated at 46. These plates pass through the slots 43. The plate 42 normally projects over the bar 28 and on the underside of the plate is carried an inking pad 47 which normally bears against the character lying on top of the plate 28. Pivotally mounted on the frame 13 is an arm 48 which has a downwardly extending portion 49 terminating in a transverse portion 50. On the underside of this portion 50 is a pad 51 of felt, rubber, or the like. Attached to the opposite end of the arm 48 is a screw 52 whereon is an adjustable collar 53 and this screw is arranged to pass through a stop member 54 secured upon the casing 11 so that provision is thus made for actuating the lever 48 at the proper moment. In the operation of this portion of the device it will be seen that as the casing 10 is depressed the plates 46 move upward with reference to the plate 42 and the parts will remain in the position shown in Fig. 1 so far as regards the paper, the inking pad, and other like parts, until the cams 46 engage what may be termed the rear end of the slots 43 with their inclined edges. This will then cause the plate 42 to move laterally within the guides 41 and when this plate had passed clear of the character lying on the bar 28, the stop

53 being properly set, the pad 51 will be forced down and carry with it the paper 35, thus causing the same to engage the characters on the bar 28 and receive an impression therefrom. At the same time, as previously described, the bill, or like piece, of paper, 70 upon which the stamp rests receives a similar impression. When the stamp is released the teeth of the toothed bar 38 engage the teeth of the ratchet 37 and rotate the drum 36, thus moving the paper to bring a fresh portion in position for receiving the impression.

There has thus been provided a simple and efficient device of the kind described, and for the purposes specified.

It is obvious that many minor changes 80 may be made in the form and construction of this invention without departing from the material principles thereof, and it is therefore not wished to confine the device to the exact form herein shown and described, 85 but it is wished to include all such as properly come within the scope claimed.

Having thus described the invention, what is claimed as new, is:—

1. In a hand stamp, a casing, paper ribbon carrying rolls movably mounted within said casing, a second casing supporting the first casing, said first casing being movable with reference to the second casing, means actuated by the movement of one of said casings with reference to the other to intermittently move said ribbon carrying rolls, duplicate sets of printing characters within the first casing, inking pads in said casings normally bearing against corresponding 100 characters in each set, said pads being moved from said characters by the movement of one casing relative to the other, a pressure pad within the first casing, said characters and pad being supported to impress one of the corresponding characters on a surface exterior to the casing simultaneous to the actuation of the pad to force a paper ribbon carried by said rolls against the other 105 corresponding character.

2. In a hand stamp, a casing, paper ribbon carrying rolls revolvably mounted within said casing, a second casing supporting the first casing, said first casing being movable with reference to the second casing, and means actuated by the movement of one of said casings with reference to the other to move said rolls intermittently, duplicate sets of printing characters within the first casing, an inking pad at the upper end of said 115 casings normally bearing against one of said characters, means to move said pad away from said characters as one casing is moved with reference to the other, other inking pads hinged at the lower part of said casings 120 and bearing against a corresponding character, the last-mentioned pads being yieldably held to move away from the last-men-

tioned character when one casing is moved with reference to the other, and a pressure pad within the first casing, said characters and pad being supported to impress corresponding characters on a surface exterior to the casing, and a paper ribbon supported on said roll.

In testimony whereof I hereunto affix my signature in presence of two witnesses.

MEREDITH G. STANLEY.
